CLAIM

I claim the ornamental design for a swimming exercise device, as shown and described.

DESCRIPTION

FIG. 1 is a front view of the swimming exercise device.

FIG. 2 is a rear view of the claimed design.

FIG. 3 is a left side view of the claimed design.

FIG. 4 is a right side view of the claimed design.

FIG. 5 is a top view of the claimed design; and,

FIG. 6 is a bottom view of the claimed design.

1 Claim, 6 Drawing Sheets

FIG. 1

FIG. 2

FIG. 3

FIG. 4

FIG. 5

FIG. 6
